[57] CLAIM

The ornamental design for a wall mountable support, as
 shown and described.

DESCRIPTION

FIG. 1 is a top, front, and left side perspective view of
 a bathroom support showing my new design as embod-
 ied in a towel bar;

FIG. 2 is a top plan view thereof, the bottom plan view
 being the same as the top plan view shown;

FIG. 3 is a front elevational view thereof;

FIG. 4 is a right side elevational view thereof, the left
 side being the mirror image of the right side shown;

FIG. 5 is a reduced top, front, and left side perspective
 view of a second embodiment of a bathroom support
 showing my new design as embodied in a towel bar, the
 only difference from the first embodiment residing in
 the greater length of the bar portion;

FIG. 6 is a top, front, and left side perspective view of
 a third embodiment of a bathroom support showing my
 new design as embodied in a toilet paper roll holder;

FIG. 7 is a top plan view thereof, the bottom plan view
 being the mirror image of the top plan view shown;

FIG. 8 is a front elevational view thereof;

FIG. 9 is a left side elevational view thereof; and,

FIG. 10 is a right side elevational view thereof.
